(57) **CLAIM**

We claim the ornamental design for a therapy device, as shown and described.

DESCRIPTION

FIG. 1 is a front perspective view of a therapy device, in accordance with an embodiment;

FIG. 2 is front view of the therapy device of FIG. 1;

FIG. 3 is a rear view of the therapy device of FIG. 1;

FIG. 4 is a left side view of the therapy device of FIG. 1; FIG. 5 is a right side view of the therapy device of FIG. 1; FIG. 6 is a top view of the therapy device of FIG. 1; and, FIG. 7 is a bottom view of the therapy device of FIG. 1.

Any portion of the article depicted in broken lines forms no part of the claimed design. The broken lines formed by dashes of equal lengths in the drawings show unclaimed subject matter. The broken lines formed by dashes of unequal lengths illustrate boundaries between claimed subject matter and unclaimed subject matter and also form no part of the claimed design. Oblique shading indicates surfaces that are transparent and/or translucent.
